UNITED STATES PATENT OFFICE.

LOUIS W. RICE, OF NEW YORK, N. Y.

DESIGN FOR A CIGAR-LIGHTER.

No. 38,901.

Specification for Design.

Patented Nov. 26, 1907.

Application filed September 6, 1907. Serial No. 391,730. Term of patent 7 years.

To all whom it may concern:

Be it known that I, LOUIS W. RICE, a citizen of the United States, residing at New York, in the borough of Manhattan, county and State of New York, have invented a new, original, and ornamental Design for Cigar-
Lighters, of which the following is a specification, reference being had to the accompanying drawing, forming part thereof.

The figure is a perspective view of a cigar-lighter showing my new design.

I claim,—

The ornamental design for a cigar-lighter, as shown.

LOUIS W. RICE.
